(57) CLAIM

The ornamental design for a garment, as shown and described.

DESCRIPTION

FIG. 1 is a front view of a garment according to the design; FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use;

FIG. 8 is a front exploded view thereof with a detachable lower portion of the garment and with detachable sleeves of the garment shown detached;

FIG. 9 is a front view thereof shown in an environment of use and with the detachable lower portion thereof shown detached and removed;

FIG. 10 is a front view thereof shown in an environment of use and with the detachable sleeves thereof shown detached and removed;

FIG. 11 is a front view shown in an environment of use and with both the detachable lower portion thereof and the detachable sleeves thereof shown detached and removed;

FIG. 12 is a front view of the detachable lower portion of the garment of FIG. 1 shown in isolation, in an opened position, and laid flat; and,

FIG. 13 is a front perspective view of the detachable lower portion of the garment of FIG. 1 shown folded into a pocket of the detachable lower portion and configured as a travel pillow or the like.

The portions of the garment shown in broken lines in FIGS. 1-13 do not form part of the claimed design. The broken line showing of the arms, legs, torso, and head in FIGS. 7 and 9-11 is for the purpose of illustrating portions of the environmental structure and forms no part of the claimed design.

1 Claim, 13 Drawing Sheets
